UNITED STATES PATENT OFFICE

WALTER C. DAVIDSON, OF NORTH CANTON, OHIO, ASSIGNOR TO THE HOOVER COMPANY, A CORPORATION OF OHIO

SUCTION CLEANER

Application filed April 18, 1929. Serial No. 356,098.

This invention relates to suction cleaners in general and particularly to dust bags for suction cleaners.

The invention consists in the novel construction of a substantially soft and open filtering material which normally lacks sufficient tensile strength to stand up under ordinary usage but which has excellent filtering qualities for separating dust from air.

The object of the invention is to provide a bag made from a substantially fragile but highly efficient filtering material, which is provided with novel means of reinforcement to take up the stretch and strain normally placed on the bag due to its connection with the cleaner operating handle.

Another object is to provide a dust bag made from a soft and substantially open filtering material which is reinforced longitudinally thereof by strips which extend substantially from the neck of the bag to the upper end thereof.

Another object is to provide a substantially porous filtering medium which is reinforced by longitudinal strips, and which is also provided with additional reinforcing at the bottom and upper end of the bag where the greatest pull and stress occurs.

Another object is to provide a cotton felt dust bag which is reinforced longitudinally thereof by means of paper strips; which is reinforced at its throat by a paper patch, and also which has a paper reinforcement at the upper or open end thereof where the closing clip is attached to the bag securing the bag to the cleaner handle.

The invention comprises, in general, a dust bag made of an open filter material such as cotton felt and which has strips of paper applied to the bag parallel with the longitudinal axis thereof. The bag also has a reinforced patch at its throat to take up the wear where the bag may touch the floor when the sweeper is being used under low places or articles of furniture. Paper reinforcement is also applied at the upper open end of the bag so that the bag may be easily emptied if desired.

The patch at the upper end reinforces the bag and equally distributes any strain which

may occur, to the longitudinal reinforcing members and the reinforced throat.

The accompanying drawing shows a selected embodiment of the invention and the views therein are as follows:

Fig. 1 is a detail side elevation of the bag showing the manner in which it is applied to a suction cleaner.

Fig. 2 is a detail sectional view on the line 2-2 of Fig. 1.

Referring to the drawing, 5 designates generally a neck or discharge outlet of a suction cleaner to which bag clamping means 6 are operatively arranged for securing the neck 7 of the dust bag 8 to the outlet 5. The bag proper is preferably made from a cotton felt material 9 and a plurality of longitudinal paper strips 10 may be suitably secured to the cotton felt to reinforce the bag.

These strips run from the neck 7 to the upper end 11 of the bag so that all strains occurring on the bag due to operating the cleaner, will be transmitted to the reinforcing strips. The upper end of the bag is preferably left open at 12 so that the bag may be easily emptied when required. This open end may be closed by means of a clip or other suitable clamping member 13 to which a flexible or yielding member 14 is secured for flexibly securing the bag to the operating handle 15 of the suction cleaner.

In order to reinforce the bag at its lower end so as to prevent chafing when the cleaner is used under low places and articles of furniture, a reinforcement or patch 16 is provided at the throat of the bag as clearly shown in Fig. 1. This patch is preferably made of paper, or of the same kind of material as the longitudinal strips 10.

Another patch 17 is provided at the upper end of the bag so that the direct pull which occurs at the upper end of the bag will be transmitted along the longitudinal reinforcing strips 10. A bag of this type has sufficient strength to stand up under ordinary usage and at the same time permits the use of cotton felt which provides one of the best filtering mediums known.

The bag may be folded along the creases shown in dotted lines in Fig. 1 so that dur-

ing normal non-operating, or rest position of the suction cleaner, the bag will flatten out and present a neat appearance for display purposes. By folding the bags along the lines described a great many bags may be stored in a very small space. This compactness adds to the desirability of a bag of this kind inasmuch as the bag will be burned or otherwise destroyed after a reasonable time and it is necessary to keep a supply on hand. The bag, however, is provided with an opening at its upper end so that it can be used for several cleanings and need not be destroyed until the bag actually wears out.

15 Changes may be made in the form, construction and arrangement of the parts without departing from the spirit of the invention or sacrificing any of the advantages thereof and the right is hereby reserved to 20 make all such changes as fairly fall within the scope of the following claims.

The invention is hereby claimed as follows:

1. A dust bag for suction cleaners comprising a body portion made of a substantially 5 open filtering material and having a reduced neck at its lower end and an opening at the upper end thereof, a reinforcing member secured on the bottom of the bag near the neck thereof, another reinforcing member ar- 10 ranged about said opening, and longitudinal reinforcements secured to the bag and extending substantially the full length thereof and spaced from each other.

2. A dust bag for suction cleaners comprising a body portion made of a cellulose fiber 35 felt material, a paper patch reinforcement ar- ranged at the lower end of the bag and at the bottom thereof, said bag having an open 40 upper end, a paper patch reinforcement ar- ranged around said open end, and longitudi- 45 nal reinforcing members extending substan- tially from end to end of said bag.

3. A dust bag for suction cleaners comprising a body portion made of cellulose fiber felt 45 and having a reduced neck and an open upper end, a reinforcing patch member secured to the felt body at the lower end of said bag and on the bottom thereof, a paper patch member arranged around the open end, lon- 50 gitudinal reinforcing members arranged on the body and extending from the bottom patch to the upper patch, and other reinforc- 55 ing members extending substantially the full length of said bag.

4. A dust bag for suction cleaners formed of loosely matted air porous material and spaced paper reinforcements secured to said 60 loosely matted material and extending sub- substantially the full length of the bag.

5. A dust bag for suction cleaners comprising a body portion formed of cellulose fiber 65 felt material and having a reduced neck, and reinforcing means secured to said bag includ- 70 ing a portion of substantial area adjacent said neck, a portion of substantial area adjacent 75 the upper end of said bag and laterally spaced

portions extending substantially the full length of the bag and connecting said other portions.

Signed at North Canton, in the county of Stark and State of Ohio, this 8th day of April, 1929.

WALTER C. DAVIDSON.
